UNITED STATES PATENT OFFICE.

ELLSWORTH A. HAWTHORNE, OF BRIDGEPORT, CONNECTICUT.

LAMP.

1,183,816.

Specification of Letters Patent.

Patented May 16, 1916.

Application filed July 21, 1913. Serial No. 780,103.

To all whom it may concern:

Be it known that I, ELLSWORTH A. HAWTHORNE, a citizen of the United States, and a resident of Bridgeport, county of Fairfield, and State of Connecticut, have invented an Improvement in Lamps, of which the following description, in connection with the accompanying drawings, is a specification, like characters on the drawings representing like parts.

This invention relates to lamps, and more especially to the means of attachment of the bezel of the lens, or other light-transmitting element or elements, to the lamp casing proper, and is more particularly concerned with features which permit the lamp to be readily converted from a bicycle headlight to a taillight, or to a marine lamp with white front light and red and green side lights.

My invention will be best understood by reference to the following specification, when taken in connection with the accompanying drawings of one specific embodiment thereof, while its scope will be more particularly pointed out in the appended claims.

In the drawings: Figure 1 is a side elevation of a lamp embodying my invention, showing the same adapted for use as a marine lamp; Fig. 2 is a plan section on line 2—2 of Fig. 1; Fig. 3 is a sectional view on line 3—3 of Fig. 1, looking toward the right; Fig. 4 is a detail rear elevation of a lens and its bezel, which may be substituted for the one shown in Fig. 1; and Fig. 5 is a rear elevation of a so-called "red jewel" and its bezel, which may also be substituted for either of the other bezels.

Referring to the drawings, and to the embodiment of my invention which I have selected for illustration, I have there shown a lamp having a casing designated generally by numeral 6, and having a laterally extending shell 7, within which may be mounted an appropriate light-producing element, as for example a lamp bulb 8. If desired, the lamp may be provided with a reflector 9, which may be and preferably is of the parabolic type. This reflector may be secured in place in any appropriate manner, but herein the shell 7 is punched out, to provide two tongues 10—10, which are bent inwardly over the front face of the marginal portion of the reflector, and serve effectually to secure the latter in place.

As shown in Fig. 1, the lamp is provided with a supplemental casing 11, attached to the main casing and provided with light-transmitting elements 13, 14 and 15. These light-transmitting elements may be of any other appropriate character, but preferably in practice the element 13 is a white front lens, and the elements 14 and 15 are what is known as red and green side jewels. The supplemental casing 11 is provided with a bead 16, which may be termed a bezel, inasmuch as it forms a part of the means of attachment of the lens, or lenses, to the main lamp casing. As herein shown, this bead is provided with an annular groove 17, which receives two lugs 18—18, appropriately formed on, or secured to the shell 7, preferably by punching or slitting the latter to form tongues and bending the latter outwardly, as clearly shown in Figs. 2 and 3, and serving as a means to secure the supplemental casing to the main casing, while allowing the same to be readily detached at will. To this end, the bead 16 is provided with a cutaway portion, or notch, 19 serving to admit one of the lugs 18 into the groove 17, and allowing the supplemental casing to be rotated to carry the lug to a position where it will be out of register with the notch.

In applying the supplemental casing to the main casing, the bead 16 is first hooked onto one of the lugs 18 while in the position indicated in dotted lines in Fig. 2, after which the other lug is introduced into the notch 19, and finally the supplemental casing is rotated practically 180 degrees, thereby to carry the lug out of register with the notch 19. As a means for limiting the rotation of the supplemental casing, the latter may be, and preferably is, provided with an inwardly bent portion 20, forming a stop which serves to engage one of the lugs 18 and limit its further movement, after being brought to the position shown in Fig. 3. If desired, this inwardly bent portion of the bead may be reinforced by placing a small drop of solder in the groove beside the inwardly turned portion. Preferably, each of the lugs 18 is given a twist or bevel, as indicated in Fig. 1, thus facilitating the entrance of the lug into the notch, and filling the groove in such a manner as to prevent the bezel from rattling.

In Figs. 4 and 5 I have shown bezels 21 and 22, having beads identical with those of

- the supplemental casing 11, and provided, respectively, with light-transmitting elements 23 and 24. The element 23 may be a white lens, and the element 24 a so-called "red jewel," one serving to transmit light when the lamp is used as a bicycle, or other vehicle, head light, and the other serving to transmit the light when the lamp serves as a tail light.
- 10 By the provision of the novel and simple attaching means already described, the lamp may be readily converted from a marine lamp to a head light or tail light, as already stated, by simply rotating the bezel until one of the lugs arrives in a position where it is in register with the notch of the bead, whereupon the lug may be withdrawn through the notch, and the other side of the bead unhooked from the other lug.
- 15 20 While I have herein shown and described one specific embodiment of my invention for illustrative purposes, and have disclosed and discussed in detail the construction and arrangement incidental to one specific application thereof, it is to be understood that the invention is limited neither to the mere details or relative arrangement of parts, nor to its specific embodiment herein shown, but that extensive deviations from the illustrated form or embodiment of the invention may be made, without departing from the principles thereof.
- 25 30 Having thus described my invention, what I claim and desire by Letters Patent to procure is:—

35 1. A lamp comprising in combination, a casing, a light-furnishing element within said casing, a light-reflecting element within

said casing, a plurality of lugs formed as integral tongues on said casing and bent outwardly therefrom, a plurality of lugs formed as integral tongues on said casing and bent inwardly to hold said light-reflecting element in place, and a bezel rotatably mounted on said casing and provided with an annular groove in which said lugs are normally located, said bezel being also provided with an opening through which one of said lugs may be introduced into said groove and turned to a position out of register with said opening.

2. A lamp comprising, in combination, a main casing, a light-furnishing element within said casing, a light-reflecting element secured within said main casing, a supplemental casing having means whereby it is capable of being instantly attached to and detached from said main casing, a light-transmitting element at the front of said supplemental casing, and a pair of light-transmitting elements one at either side of said supplemental casing, said supplemental casing with its light-transmitting elements constituting a unitary structure individually distinct from said main casing, temporarily attached thereto, and adapted to be removed without disturbing said light-reflecting element.

In testimony whereof, I have signed my name to this specification, in the presence of two subscribing witnesses.

ELLSWORTH A. HAWTHORNE.
